UNITED STATES PATENT OFFICE

91,257

DESIGN FOR A CASH REGISTER CABINET

Harry J. Williams, Dayton, Ohio, assignor to The
National Cash Register Company, Dayton,
Ohio, a corporation of Maryland

Application April 24, 1933. Serial No. 47,866

Term of patent 14 years

To all whom it may concern:

Be it known that I, HARRY J. WILLIAMS, a citizen of the United States, residing at Dayton, in the county of Montgomery and State of Ohio, have invented a new, original, and ornamental Design for Cash Register Cabinets, of which the following is a specification, reference being had to the accompanying drawings, forming part thereof, in which—

Fig. 1 is a perspective view showing the front, right side and top of the cabinet.

Fig. 2 is a perspective view showing the back, left side and top of the cabinet.

Fig. 3 is a side elevation of the cabinet.

The design is characterized by its configuration as well as its ornamentation.

In its ornamentation the design comprises panels (shown stippled) outlined by plain strips or bands, the panels and bands being given distinguishing finishes to aid in producing the desired contrast between them.

The bands may be raised or flush with that part of the cabinet shown stippled if desired.

What is claimed is:

The ornamental design for a cash register cabinet, as shown and described.

In testimony whereof I affix my signature.

HARRY J. WILLIAMS.
